(57) **CLAIM**

The ornamental design for a bone plate, as shown and described.

DESCRIPTION

FIG. 1 is a top perspective view of a bone plate showing our new design;

FIG. 2 is an end elevation thereof;

FIG. 3 is a top plan view thereof;

FIG. 4 is a right side elevation thereof, the side opposite being a mirror image;

FIG. 5 is a bottom plan view thereof; and,

FIG. 6 is an elevation thereof of the end opposite that shown in FIG. 2.

The broken lines shown in the drawings are included for the purpose of illustrating structural environment and form no part of the claimed design.
